PORTABLE ELECTRIC PUMP

Ralph L. Barmore, Wichita, Kans.

Application January 29, 1953, Serial No. 23,343

Term of patent 3½ years

(Cl. D65—1)

To all whom it may concern:

Be it known that I, Ralph L. Barmore, a citizen of the United States, residing at Wichita, State of Kansas, have invented a new, original, and ornamental Design for a Portable Electric Pump, of which the following is a specification, reference being had to the accompanying drawing.

Figure 1 is a perspective view showing the top, one side and one end of a portable electric pump embodying my new design.

Figure 2 is an end view taken from the left of Figure 1; and

Figure 3 is an end view taken from the right of Figure 1.

The side not shown is identical with the side shown.

I claim:

The ornamental design for a portable electric pump, as shown and described.

RALPH L. BARMORE.
